JOHN M. D. KEATING AND THOMAS V. WAYMOUTH, OF NEW YORK, N. Y. #

Letters Patent No. 91,025, dated June 8, 1869.

IMPROVEMENT IN MACHINES FOR MAKING PAPER BOXES.

The Schedule referred to in these Letters Patent and making part of the same.

To all whom it may concern:

Be it known that we, JOHN M. D. KEATING and THOMAS V. WAYMOUTH, of the city, county, and State of New York, have invented certain new and useful Improvements in Machines for Making Paper Match-Boxes, Envelopes, &c.; and we do hereby declare the following to be a clear and exact description of the same, reference being had to the accompanying drawings, figures, and letters of reference thereon, making part of this specification.

Of the said drawings—

Figure 1 is a perspective view of a machine embodying our improvements.

Figure 2 is a top view of the plate B.

Figure 3 is a side view elevation of a portion of the machine.

Figures 4 and 5 are views of the die which forms up the blank.

Figures 6 and 7 show a paper-blank and a box.

Similar letters of reference indicate like parts in all the drawings.

Our invention consists—

First, in the combination, with a plunger, of a die, constructed with the grooves and inclines shown so as to fold, lap, and unite the previously-cut and gummed blanks, as they are forced through the die by the plunger.

Second, in the employment and use of receiving-boxes upon an endless belt, so constructed as to receive, hold, and convey the boxes for the successive operations of gumming and sanding.

Third, in the combination, with the receiving-boxes, endless belt, gum-fountain, and sand-box, of a lifter for forcing the sand into contact with the bottom of each box.

Fourth, in constructing the sand-box of flexible material.

Fifth, in the combination, with the receiving-boxes and endless belt, of a plunger for discharging the paper boxes from the receiving-boxes.

To enable others skilled in the art to make and use our invention, we will describe the construction and operation of the same.

Secured to a proper bed are the uprights A A, of the frame, which are bolted together in any proper manner, and in the centre of this frame is a main shaft, C, which is the prime mover of all the parts.

To the upper part of the frame A, is secured a box, in which a bar, H, reciprocates, and by means of brackets h and t, carries the plunger I and gummers j j.

The lower end of this reciprocating bar H, is forked, and straddles the main shaft C, and it receives its motion from a roll on a stud attached thereto, and the cam E.

On the main shaft C, is a cam, F, which, by means of a lever, d, secured to a rock-shaft, L, and a lever.

P, reciprocates the nippers k k, which slide in grooves r r, on the top plate B of the machine.

On the main shaft C, is a cam, g, on the inside of the frame A, and directly back of the cam F, which operates a lever, m', which has its fulcrum on the shaft L, and by a connecting-rod a', connects with a short lever, b', pivoted on the shaft M, which lever carries a ratchet-finger, which, in conjunction with a ratchet-wheel, e, on the shaft, rotates the shaft, and consequently the endless belt N, by means of a square arbor secured to the shaft, which square arbor receives a quarter revolution at each revolution of the main shaft C.

On the main shaft C, is another cam, G, which, by means of a stud, operates the lever f, and through the medium of a connecting-rod and elbow-lever d, reciprocates a slide, b, which carries a gumming-roller, n. These cams are all of such shape as to give the required motion to the working-parts, and are all reacted upon by coil-wire springs.

The lever P, which is secured on the shaft L, has an elbow, x, and as it is vibrated, carries a lifter, w, to bring the sand-box U in contact with the ends of the boxes, as they pass over the sand-box. Upon this lever is an arm, projecting downward, and this arm connects with a rocking lever, z, which is connected with a bracket, secured to a frame by a rod. The upper end of this vibrating lever engages with the plunger d', which discharges the paper boxes from the receiving-boxes. This discharging-plunger slides in a proper groove or grooves, on a plate secured to the frame of the machine.

On the upper side of this plate is secured the reservoir or fountain, V, for gumming the ends of the boxes. This reservoir is provided with a roll, e', which, by the friction of the endless belt, rotates intermittently, and, as the ends of the paper boxes which project through the receiving-boxes are drawn over this roll, a sufficient quantity is applied to the end of the box for causing the sand to adhere.

The distributing-roller o, which supplies the gumming-roller n, is driven by a belt, or cord, passing from the pulley C on the main shaft, to the pulley g', on the shaft of the distributing-roller.

The drum K, over which the endless belt passes, is secured in brackets r v, which are bolted to the frame. The brackets are slotted longitudinally, so that the endless belt can be kept sufficiently taut.

The construction of the nippers and the operative mechanism will be readily understood from an inspection of the drawing, figs. 2 and 3.

The spring-arms k k, are secured to a shaft, which has its bearings in brackets attached to the slide k', and the arms k k are held to the plate by a spring on the shaft arranged for the purpose.

*Ass'ts to Gordon Conkling Jr. of same place.

Operation:

The operation of the machine will be as follows: The reservoirs V W being supplied with gum, and the sand-box U in proper condition, the pile of paper-blanks S, of the shape shown in fig. 6, is laid in the box r, on the plate a.

The shaft C is made to revolve by proper mechanism, and while the plunger I is at its highest point and at rest, the roll n, which has been in contact with the distributing-roller o, in the gum-reservoir W, passes back and forth under the pieces j j, on the rods, and coats them with the proper supply of gum. The pieces j j then descend upon the pile of blanks—the coil-spring upon the rods adjusting the rods to the thickness of the pile of blanks—and lift the blanks to the plate b.

The nippers k k now come forward, and by means of the pin in the lever l, travelling upon the incline j, open so as to pass over the blank, and as the pin drops over the incline, the nippers clamp the blank to the inclined projection n', and, as the nipper-plate k' recedes, the blank is carried forward so that the end-flaps r', will be directly under the plunger I. The plunger now descends, doubles the blank into the die, and in the descent passes the blank down the inclines o' o', fig. 5, in the die, which fold the inside flaps, while the outside flaps are gradually folded in the grooves k' k' in the die, and as the plunger descends, the gummed flaps are lapped to the flaps p' p', fig. 6, and by pressure in the lower part of the die, are made to adhere firmly together, and the plunger still descending, forces the folded box into the receiving-boxes. The plunger is withdrawn and the operation repeated.

The paper box in the receiving-box is then carried forward by the endless belt, and the end of the paper box which projects through the receiving-box, drags over the gum-roller e', which coats it with gum, and when directly over the sand-box, the lifter w is raised,

and the sand in the box is brought in contact with the end of the box, and a sufficient quantity will adhere thereto for striking the match. The box is then carried forward on the endless belt until punched out by the discharging-plunger d'.

The receiving-boxes N are secured to the perforated endless belt, N, in any proper manner, and they are bell-mouthed, so that the plunger and paper box will readily enter them.

Having thus fully described our invention, What we claim, and desire to secure by Letters Patent, is—

1. The combination, with the plunger I, of the double die T, constructed with grooves and inclines at both sides, as shown, so as to double-lap and unite the previously-cut and gummed blanks as they are forced through the die by the plunger, substantially as described and specified.

2. The employment and use of the receiving-boxes upon the endless belt, so constructed as to receive, hold, and convey the paper boxes for the successive operations of gumming and sanding the ends of the same, substantially as described and specified.

3. The combination, with the receiving-boxes and endless belt, the gum-fountain and sand-box, of the lifter for forcing the sand into contact with the end of each box, substantially as described and specified.

4. Constructing the sand-box of flexible material, substantially as described and specified.

5. The combination, with the receiving-boxes and endless belt, of the plunger for automatically discharging the paper boxes from the receiving-boxes, substantially as described and specified.
